DESIGN FOR AN ADHESIVE TAPE DISPENSER

Theodore H. Krueger, Stratford, Conn., assignor to Better Packages Incorporated, Shelton,
Conn., a corporation of New York

Application June 8, 1946, Serial No. 130,538

Term of patent 14 years

(Cl. D74—1)

To all whom it may concern:

Be it known that I, Theodore H. Krueger, a citizen of the United States, residing in Stratford, county of Fairfield, and State of Connecticut, have invented a new and original and ornamental Design for an Adhesive Tape Dispenser, of which the following is a specification, reference being had to the accompanying drawing, forming part thereof.

The figure is a perspective view of an adhesive tape dispenser, showing my new design, the back being plain and the opposite side presenting the same appearance as the side shown.

I claim:

The ornamental design for an adhesive tape dispenser, substantially as shown and described.

THEODORE H. KRUEGER.
